UNITED STATES PATENT OFFICE.

ALFRED J. ASHFORD, OF KINSTON, NORTH CAROLINA.

NON-REFILLABLE BOTTLE.

No. 815,250.

Specification of Letters Patent.

Patented March 13, 1906.

Application filed May 24, 1905. Serial No. 261,967.

To all whom it may concern:

Be it known that I, ALFRED J. ASHFORD, a citizen of the United States, residing at Kinston, in the county of Lenoir and State of North Carolina, have invented new and useful Improvements in Non-Refillable Bottles, of which the following is a specification.

My invention relates to improvements in what are usually termed "non-refillable bottles," otherwise known as "bottle-valves."

As noted, objects of the invention are primarily to guard against the unauthorized refilling of the bottle and to accomplish this in a simple, inexpensive, and effective manner; and to these ends the nature of the invention consists of certain structural features substantially as hereinafter fully disclosed and particularly specified.

In the accompanying drawings, illustrating the preferred embodiment of my invention, Figure 1 is an axial or longitudinal section of the bottle. Fig. 2 is a horizontal section produced through the bottle just above the valve. Fig. 3 is also an axial section of the same inverted, as when discharging or emptying its contents.

In the carrying out of my invention I suitably form or produce the bottle 1 in any well-known way with a horizontal partition 2, arranged well up near the conjunction of the body and the neck, and provide said partition with a central opening 2^a for the passage of the liquid or contents of the bottle, as in initially filling the latter and in emptying or outpouring said contents. The neck portion of said bottle is caused to jut or extend at its inner end into the body portion thereof a short distance, as at 3, the extension thus formed being preferably externally beveled toward the inner upper surface of the body portion to reduce to the minimum any otherwise-formed obstruction to the passage of the bottle contents beyond or outward of the partition 2. Said jutting portion or extension 3 of the bottle-neck is provided with numerous holes or passages 4, communicating with the space or supplemental chamber 4^a, formed above the partitions 2, said passages also communicating with the outlet or interior of the bottle-neck, thus constituting, with the valve in position, as presently noted, a tortuous or indirect course for the flow of the liquid or contents from the bottle in discharging said contents.

Seated in the opening or passage 2^a of the partition 2 is a preferably disk-like valve 5, with its under side normally resting upon an upraised surface or elevation 2^b of said partition and its downward-extending stem depending through said opening or passage for the restriction or limitation of the movement of said valve, resulting from the inverting of the bottle, &c. Said valve, it will be noted, is limited in its play or movement as between the jutting or depending portion 3 of the neck portion and the upraised surface or elevation 2^b around the upper edge of the opening or passage 2^a through the medium of these parts, and is rendered thereby effective against being displaced by any attempt by unauthorized persons with the view of refilling the bottle; yet it will be observed that in inverting the bottle, as when desiring to discharge its contents or the contained liquid, the valve 5 will automatically unseat from over the opening 2^a and permit the flow of the liquid through the latter, the valve at the same time oppositely seating over the inner end of the bottle-neck or rather the extension 3 thereof, thus closing said end of the bottle-neck, while the liquid will be allowed to flow through the lateral passages 4 of the latter and enter and pass out through the neck. As the bottle is restored to its normal or upright position the valve 5 will likewise automatically resume its original position or seat. Also it is noted that regardless of whatever position or angle the bottle may be caused to assume the valve 5 will always be in effective alinement or contiguity with the opening or passage 2^a and so guard against the uncovering thereof by any effort to dislodge said valve through the bottle-neck, the only channel by which access could be had to said opening or valve.

It will be noted that by arranging the valve-seating partition 2 within the body portion of the bottle and jutting or extending the neck portion or member thereinto a relatively increased quantity of the contents of the bottle is admitted directly to said neck or delivery portion for discharging said contents with facility. Also by this arrangement of parts it will be seen that the number of the baffling parts is reduced to the minimum and the construction of said baffling parts greatly simplified. Further, by such disposition of parts the neck or mouth of the

bottle is left wholly free of any obstructions, as in arranging therein the baffling parts—such as partitions, valves, and their seats, &c.

I claim—

- 5 A non-refillable bottle having its neck portion constituted of a cylindric formation practically continued into its body portion, the neck extension thus produced being provided with lateral apertures opening into said
- 10 body portion, said latter portion having an integral apertured partition subdividing the interior therefor, a short distance inward from the inner end of said neck extension, and a gravity-valve tapered in general out-
- 15 line with its tapered portion normally filling

the aperture of said partition, and having a flat circular face presented toward and effective to seat against said inner end neck extension when the bottle is tilted or inverted and simultaneously with which seating action said valve is so shifted with relation to said aperture as to permit the passage by it of the bottle contents. 20

In testimony whereof I affix my signature in presence of two subscribing witnesses.

ALFRED J. ASHFORD.
